UNITED STATES PATENT OFFICE.

JOHN P. DRESP, OF BEATRICE, NEBRASKA, ASSIGNOR TO BEATRICE STEEL TANK
MANUFACTURING COMPANY, OF BEATRICE, NEBRASKA, A CORPORATION OF
NEBRASKA.

METALLIC CORNER-SHIELD.

1,211,109.

Specification of Letters Patent. Patented Jan. 2, 1917.

Application filed January 30, 1915. Serial No. 5,264.

To all whom it may concern:

Be it known that I, JOHN P. DRESP, a citizen of the United States, residing at Beatrice, in the county of Gage and State of Nebraska, have invented certain new and useful Improvements in Metallic Corner-Shields, of which the following is a specification, reference being had to the accompanying drawings.

This invention relates to certain improvements in metallic corner shields and has relation more particularly to a device of this general character especially designed and adapted for use in connection with corners of buildings where lapsiding is employed; and the object of the invention is to provide a novel and improved device of this general character whereby a convenient connection is produced at the meeting ends of the sidings at the corners of a building and affording a maximum of strength.

The invention consists in the details of construction and in the combination and arrangement of the several parts of my improved metallic corner shield whereby certain important advantages are attained and the device is rendered simpler, less expensive and otherwise more convenient and advantageous for use, all as will be hereinafter more fully set forth.

The novel features of the invention will be carefully defined in the appended claim.

In order that my invention may be the better understood, I will now proceed to describe the same with reference to the accompanying drawings, wherein—

Figure 1 is a fragmentary view in perspective of a corner of a building structure, showing a corner shield constructed in accordance with my invention in applied position thereon; Fig. 2 is an enlarged horizontal section taken through a shield adjacent the base thereof; Fig. 3 is a sectional view taken substantially on the line 3—3 of Fig. 2, looking in the direction of the arrow; and Fig. 4 is a view in plan of a blank from which my improved device may be produced, the different lines of bend being indicated by dotted lines thereon.

As disclosed in the accompanying drawings, 1—1 denote the integrally connected wings of a corner shield constructed in accordance with an embodiment of my invention and disposed on requisite relative angles and having produced adjacent their free

longitudinal edges the openings 2—2 through which suitable anchoring means are adapted to be directed and the lower marginal portions of the wings are turned or flexed inwardly to afford the flanges 3, the adjacent extremities of the flanges overlapping as indicated at 4 in order to reinforce the device. It is to be particularly observed that the adjacent extremities of the flanges 3 are adapted to overlap by bending or flexing the material whereby an intermediate ply or layer 5 of metal is provided whereby the strength of the device is greatly enhanced and the maintenance of the wings at their requisite relative angles is positively assured.

As is believed to be obvious, my improved corner shield is produced from a single blank α of material bent or flexed longitudinally at substantially its longitudinal center b with the lower extremity flexed inwardly on the transverse line c to afford the flanges 3, and the adjacent extremities of the flanges 3 are flexed on the diagonal lines d in order to provide for the intermediate ply 5 or layer 5.

In practice, the wings 1 are adapted to overlie the adjacent extremities of the boards at the corner of the building while the flanges 3 are adapted to overlie the lower edge portions of the extremities of such boards, in a manner which is believed to be self-evident, and it will be readily perceived that by the use of a device of this general character a miter corner effect is produced with a minimum of labor and expense, and that my improved metallic corner serves as an effective medium to prevent the boards from warping apart. It is also to be observed that certain of the openings 2 are in close proximity to the flanges 3 while the remainder of such openings are at substantially midway the length of the wings.

From the foregoing description, it is thought to be obvious that a metallic corner shield constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be un-

derstood as limiting myself to the precise arrangement and formation of the several parts herein shown in carrying out my invention in practice.

5 I claim:

As a new article of manufacture, a metallic corner shield for lapsiding comprising perpendicularly disposed integral wings having their lower end margins turned inwardly to afford flanges, said flanges being integrally connected, the adjacent extremi-

ties of the flanges overlapping and being flexed to afford an intermediate ply at their overlapping portions to strengthen the device and to maintain the wings at their 15 requisite relative angles.

In testimony whereof I hereunto affix my signature in the presence of two witnesses.

JOHN P. DRESP.
